METAL VAPORIZATION CRUCIBLE WITH UP-STANDING WALLS FOR CONFINING AND CONDENSING VAPOR

Waldo Rall, Fox Chapel Borough, Pa., assignor to United States Steel Corporation, a corporation of Delaware
Continuation of application Ser. No. 482,193, Aug. 24, 1965. This application Jan. 19, 1968, Ser. No. 703,509
2 Claims. (Cl. 266—39)

ABSTRACT OF THE DISCLOSURE

A crucible for holding molten metal, provided with a wall around the metal bath and extending upwardly therefrom to confine vapor ascending from the bath surface and condense vapor not moving directly toward the material above the bath to be coated by condensation thereon. Metal condensed on the wall runs down back into the bath.

This is a continuation of my application Ser. No. 482,193, filed Aug. 24, 1965, now abandoned.

This invention relates to a crucible for the vaporization of metal. In particular, the invention concerns a crucible having a confining structure formed by a wall extending upwardly therefrom. This structure serves to confine the evolving vapor and affords a surface for the condensation of such portion of the vapor cloud as may tend to have a random direction and to depart from the desired course of travel.

In the generation of metal vapor, as for example, in apparatus for the coating of sheet material by the condensation of metal vapor thereon in a vacuum, it is desirable that the metal vapor travel from the source, usually a top-heated boiling bath of molten metal, directly to the substrate to be coated. It is inevitable, however, that some substantial portion of the ascending vapor cloud will have a random direction of travel and will impinge and condense on some part of the coating apparatus instead of the substrate. This is objectionable not only because of the loss of metal vapor but, even more importantly, because accumulations of condensed vapor at random locations will, in time, require complete shut-down of the apparatus for clean-out. Downtime directly reduces the possible output of the apparatus and increases the total unit cost of the product.

It is accordingly the object of my invention to provide means for confining the ascending vapor cloud and tending to direct it toward the substrate and, further, to provide such means of a character which will serve to condense vapor not traveling directly toward the substrate and return it to the boiling bath for re-vaporization. My invention contemplates the provision, over a vaporization crucible, of a wall confining the ascending vapor cloud, of such nature that, in the normal operation of the crucible, it will be heated to a temperature above the melting point of the metal being vaporized but below the temperature at which vapor impinging thereon will be immediately reflected by thermal emission. As a result, the random-directed vapor impinging on the confining walls condenses to liquid form and runs downwardly therealong back into the crucible. The remainder of the vapor traversing the desired course, continues thereon until it condenses on the substrate traveling above the wall.

A complete understanding of the invention may be obtained from the following detailed description and explanation which refer to the accompanying drawings illustrating the present preferred embodiment. In the drawings:

FIGURE 1 is a plan view of metal-vaporization apparatus incorporating my invention; and

FIGURE 2 is a section therethrough taken along the plane of line II—II of FIGURE 1 and showing the relative path of the substrate traveling over the crucible.

Referring in detail to the drawings, a crucible 10 may be conveniently composed of a metal receptacle 11 having a lining 12 of a refractory material which is not significantly attacked by molten aluminum, e.g., boron nitride. A charge of metal 13, such as aluminum, in the crucible 10 is adapted to be melted and vaporized by top heating. In the example illustrated, heating is effected by electron bombardment. A source of electrons is afforded by an electron-beam gun 14 extending alongside crucible 10 and maintained at a high, (i.e. several thousand volts) negative potential relative thereto.

A side wall 15, generally similar in outline to the crucible, extends upwardly from the edges thereof. The side wall is provided with an entry port 16 for a beam of electrons from gun 14. Means (not shown) whereby they traverse a curved path, such as a direct current magnetic field, are provided, so they ultimately impinge on the top of charge 13. A ring 17 restricts the beam for entry into port 16 with a minimum of bombardment of the edge thereof.

Wall 15 has a lining 18 of a material resistant to the effect of contact by metal vapor, e.g., aluminum vapor, from crucible 10. This material may be alumina, boron nitride, aluminum nitride, zirconia or silicon nitride, or a mixture thereof. Wall 15 may be composed entirely of such material but usually a lining thereof having a thickness of the order of .010" or .015" will suffice. The lining is applied over a backing of thermal insulating material of any suitable character.

A substrate 19 to be coated with metal is conducted across the top of wall 15 by any convenient means not shown and, of course, the entire apparatus shown is enclosed in a vacuum chamber which is pumped down to a suitable low pressure such as 1 micron of mercury or lower.

It will be evident that metal vapor boiling off the surface of the molten charge 13 will form an ascending cloud most of which will eventually reach substrate 19 and condense thereon to form a coating on the lower surface thereof. Some of the vapor will, however, condense on the interior of wall 15, or, more specifically, on lining 18. Such portion will remain liquid because of heat radiated from charge 13 and because of the heat of vaporization liberated when the vapor condenses, and when collected into globules of sufficient size, will run down side wall 15 and back into charge 13 for further heating therein and re-vaporization therefrom. The side wall is made of a thick, heat insulating material and may be further surrounded by a radiant-heat shield, not shown, so as to retain as much as possible of the radiant heat and heat of condensation to assure that the condensate does not solidify and build up but returns to the crucible as liquid.

Side wall 15 thus acts in two ways, first it generally confines the vapor in an upward path toward the substrate and second, it serves as a condenser for vapor which because of its direction of travel, would not impinge on the substrate in any event. As a result, a large part of the vapor actually reaches the substrate and that which does not is promptly returned to the crucible in liquid form.

The invention obviously improves the efficiency with which metal is deposited on the substrate, but what is more important, it prevents fouling the adjacent portions of apparatus in the vacuum chamber with an unwanted accumulation of aluminum condensed from the vapor intended for coating.

Although I have disclosed herein the preferred embodiment of my invention, I intend to cover as well any change

or modification therein which may be made without departing from the spirit and scope of the invention as set forth in the claims.

I claim:

1. In a metal-vaporization apparatus including a crucible adapted to contain a charge of molten metal for deposit on a substrate spaced above the crucible, and means for top-heating the charge to vaporize the metal, the combination therewith of a side wall extending around the greater portion of the edge of the crucible, at least, and from the crucible substantially to the substrate enclosing the space above the crucible and confining the vapor but allowing free ascent of vapor from the charge in a generally vertical direction, said wall having its inner face, at least, composed of a material selected from the group consisting of alumina, zirconia, aluminum nitride, boron nitride and silicon nitride and being thereby adapted to condense into liquid form the vapor striking it and con-

duct the resulting liquid metal downwardly back into the crucible.

2. Apparatus as defined in claim 1, characterized by said top-heating means being an electron-beam gun adjacent the crucible, said side wall having an opening therein to admit the beam from said gun.
